UNITED STATES PATENT OFFICE

ARQUÍMEDES CAPITAN, OF DAVID, PANAMA.

TRAIN-SIGNAL.

1,331,318.

Specification of Letters Patent.

Patented Feb. 17, 1920.

Application filed September 9, 1916. Serial No. 119,323.

To all whom it may concern:

Be it known that I, ARQUÍMEDES CAPITAN, a citizen of the Republic of Chile, residing at David, in the Province of Chiriquí and Republic of Panama, have invented certain new and useful Improvements in Train-Signals; and I do hereby declare the following to be a full, clear, and exact description of the invention, such as will enable others skilled in the art to which it appertains to make and use the same.

This invention relates to new and useful improvements in train signals and the principal object of the invention is to provide a signal to the engineer of the locomotive should the train run by a semaphore set at danger.

Another object of the invention is to provide a device which will be operated upon the passing of a train by a semaphore signal to ring a signaling bell or operate the brake setting mechanism and the like.

A still further object of the invention is to provide a device containing improvements over the device illustrated in my copending application filed March 8, 1916, Serial No. 82,882.

With these and other objects in view, the invention consists in the novel combination and arrangement of parts which will be fully set forth in the following specification and accompanying drawing, in which:—

Figure 1 illustrates the device as it would appear applied to a locomotive and set ready for operation, and

Fig. 2 is an enlarged detail view of the apparatus showing the wiring diagram for operating a bell or similar signal.

Referring to the drawing the numeral 1 designates a locomotive of the ordinary structure while the numeral 2 designates the standard of a semaphore signal. The semaphore arm 3 is pivoted to the standard in the ordinary manner and is provided with the blade 4 which extends outwardly from the end of said arm so that when the arm moves to danger position the blade will lie in the path of the mechanism carried by the locomotive.

50 The locomotive attachment consists of a standard or supporting arm 5 which projects outwardly from the cab of the locomotive and supports at its outer end a substantially U-shaped support including a vertical bar 6 provided at its upper and lower

terminals with the outwardly extending arms 7 and 8. The arm 7 is provided at its outer end with a suitable eye 9 while the arm 8 is provided with a groove 10 in its under side which groove is curved as at 11 to form 60 a guide for the operating cord of the device. A bolt 12 is slidably mounted in an opening 13 formed in the side of the path of the locomotive and a suitable sleeve 14 is secured to the inner side of the cab around the opening 13 as clearly illustrated in the drawing. The bolt 12 is provided at its outer end with the eye 15 while the inner end carries the head 16 and a suitable compression coil spring 17 surrounds the bolt and abuts the 70 inner side of the head 16 and the inner side of the wall of the cab. It will thus be seen that the bolt will tend to move inwardly under the influence of the spring 17. A suitable arm 18 is carried by the bolt and provided with the upturned finger 19 for engagement against the contact spring 20 so that upon inward movement of the bolt the said spring will move into contact with the contact finger 21 so as to complete an electric 80 circuit through any suitable signaling means or through a suitable mechanism for operating the train control devices. In order to hold the bolt outwardly so that the spring 20 will not engage the finger 21 85 a suitable core or flexible member 22 is provided and one end thereof is attached to the eye 9 while the opposite end passes through the curved portion 11 and groove 10 and is connected as illustrated in the drawing to 90 the eye 15.

It will be apparent from the foregoing that in use the device is connected in the manner illustrated in Fig. 1 and the cord or flexible member 22 is of such a length as 95 to hold the bolt outwardly against the compression of the spring 17 so that the spring 20 will disengage the contact finger 21. When the train runs by a signal it will be evident that the cord will be cut by the 100 blade 4 and the bolt will move inwardly under the influence of the spring 17 to move the spring 20 into engagement with the finger 21 and thereby complete an electric signaling circuit or any other suitable train 105 carried signaling means.

While in the foregoing there has been shown and described the preferred embodiment of this invention, it is to be understood that such changes may be made in the combi- 110

nation and arrangement of parts as will fall within the spirit and scope of the appended claim.

What is claimed is:—

- 5 The combination with a vehicle including a wall, of a bracket connected with the outer face of the wall and having outwardly extending arms, one of the arms being provided with a longitudinally extending
- 10 groove, a plunger extending through an opening formed in the wall and provided with an enlarged head at its inner end, a spring positioned about the plunger between the head and wall to yieldably retain the plunger in a
- 15 normal position, a circuit closer having contact arms, one of the arms being connected

with the head of said plunger, and a line of breakable material connected with the outer end portion of the plunger and extending through the groove and carried across the 20 space between the arms of said bracket and connected with the second arm, said line retaining the plunger in a set position against the action of the spring to retain the arms of the circuit closer out of engagement until 25 the line is broken.

In testimony whereof I affix my signature in presence of two witnesses.

ARQUÍMEDES CAPITAN.
